UNITED STATES PATENT OFFICE.

EDWARD J. O'KEEFE, OF NEW YORK, N. Y., ASSIGNOR, BY MESNE ASSIGNMENTS, TO P. & F. CORBIN, OF NEW BRITAIN, CONNECTICUT.

LOCK.

SPECIFICATION forming part of Letters Patent No. 414,720, dated November 12, 1889.

Application filed January 18, 1889. Serial No. 296,692. (No model.)

To all whom it may concern:

Be it known that I, EDWARD J. O'KEEFE, a citizen of the United States, and a resident of New York, in the county of New York and 5 State of New York, have invented certain new and useful Improvements in Locks, of which the following is a specification.

The invention relates to improvements in locks; and it consists in novel devices hereinafter described, whereby the lock may be 10 opened by either of two keys different in outline.

The purpose of the invention is to provide 15 a lock for buildings—such as hotels—having a large number of rooms, having tenants for each, and necessitating the providing of keys for the tenants, as well as for the janitor or persons cleaning the various apartments or having general inspection of them.

20 By means of my invention the separate rooms of a hotel or other building may be provided with the locks, and the tenants each supplied with a key which will open the doors of their respective apartments, but which will 25 not serve to unlock the doors of the adjoining apartments, and the porter or janitor supplied with a single key by which all of the locks of the building may be opened, the janitor thus with one key being enabled to enter 30 any of the rooms, while the tenants, holding different keys, may also be enabled to enter their own respective apartments.

The invention will be more fully understood from the detailed description hereinafter presented, reference being had to the accompanying drawings, in which—

Figure 1 is a view of a detached portion of a door employing the lock, the lock and door being partly in section on the dotted line X X 35 of Fig. 3. Fig. 2 is a central vertical section through the lock on the dotted line Y Y of Fig. 1, the parts of the lock being illustrated in the position they are caused to assume by the insertion of one of the keys, which, for 40 convenience, may be styled the "minor" or tenant's key. Fig. 3 is a like view of the lock with its parts illustrated in the position they are caused to assume by the introduction 45 of a different key, styled the "major"

or janitor's key. Fig. 4 is a face view of the 50 minor key. Fig. 5 is a like view of the major key, and Fig. 6 a face view of the inner end of the escutcheon-cylinder.

In the drawings, A designates the door, which will be supplied with the usual knob-spindle B and spring-latch bolt C; these elements forming no part of the present invention.

The escutcheon-cylinder is designated by the letter D, and has a threaded exterior, by 60 which it is secured in position in an aperture formed in the door A and corresponding with an aperture formed in the lock-casing E, said cylinder being retained in said apertures by means of its threaded exterior in connection 65 with the locking-rod F, (illustrated in Fig. 1,) said rod being adapted to be driven against the threaded cylinder by means of the screw G, the head of which is exposed at the edge of the door, the rod F also forming no part of 70 the present invention.

The escutcheon-cylinder D contains the cylinder H and cylinder I, one closely fitting the other and the whole inclosed by the cylinder D.

In the cylinder D are formed the series of chambers J, containing springs K and drivers L, adapted, through the action of the springs K, to depress the pins lettered M N, respectively, which move in chambers or apertures 80 formed in the cylinders H I, as illustrated in Figs. 2 and 3. The outer edge of the cylinder H has a shoulder O seated in an annular recess in the adjoining edges of the cylinder D, and the cylinder I has at its outer edge 85 a shoulder P seated in a correspondingly-formed recess in the inner edges of the cylinder H, the purpose of the shoulders O P being to insure the due rotation of the cylinders H I when actuated by the keys. The 90 cylinder I contains a slot Q for the reception of either the minor key R or the major key S. The inner edge of said cylinder I is provided with an annular groove T, which rotates against the locking-plate V, the edge of 95 said plate resting in said groove and serving to prevent the cylinder I from being drawn outward from the lock. The inner central

portion of the cylinder I is provided with a recess to receive the inner end of the rod W, which carries a ward *a* of a size adapted to enter the slot Q, in which position it is illustrated in Figs. 2 and 3. The rod W extends through the lock-casing from the inner side of the door, where it is provided with a hub *b* and shoulder *d*. The outer portion of the rod W is inclosed by the casing *e*, in which a chamber *f* is provided to receive the spring *g* between a shoulder formed in it and the collar *d*, as illustrated in Fig. 2. The collar *d* is retained on the rod W by means of the sleeve *i* and set-screw *j*. The rod W within the locking-casing passes through the revolute plate *k*, which contains a central aperture fitting the surface of the rod W and a slot *m*, corresponding with the slot in the inner end of the cylinder I to receive the ward *a*. The revolute plate *k* carries the arm *n*, and is provided with an annular groove *p*, fitting and having a movement upon the edges *q* of the lock-casing, as illustrated in Figs. 2 and 3. The rod W may have a horizontal movement through the plate *k* without rotating it, the plate being prevented from having any but a rotary movement by means of its annular groove *p* and the edges *q* of the lock-casing. When the rod W is caused to rotate either by the operation of turning the cylinder I by means of the key or by pressure applied to the head *b*, the ward *a* on said rod will engage the slot *m* in the plate *k* and cause said plate to have a rotary movement, whereby the arm *n* is brought into contact with the tumbler *r*, elevating it, and then against the walls of the recess *s*, formed in the bolt *t*, as illustrated by dotted lines in Fig. 1, the purpose of the arm *n* during this movement being to first free the bolt *t* by elevating the tumbler *r*, and then to either project the said bolt into the usual nosing or retract it into the lock-casing. The bolt *t* will be supported and guided in its movement by the face-plate *w* and the pin *x*, arranged in the elongated slot *y*. (Illustrated by dotted lines in Fig. 1.)

When desiring to open the lock from the inner side of the door, it will be necessary to draw the head *b* outward from the door, thereby compressing the spring *g* in the chamber *f* and withdrawing the inner end of the ward *a* from the slot Q in the cylinder I, thus leaving said ward fully engaging the slot *m* in the revolute plate *k*, whereupon by turning the head *b* the arm *n* is caused to move upward, elevating the tumbler *r* and retracting the bolt *t* into its casing. When the rod W is withdrawn from the cylinder I, by drawing on the head *b* the plate *k*, with its arm *n*, may be caused to fully lock or unlock the door by the rotation of the head *b*, which, as aforesaid, is on the inner side of the door.

The operation of the cylinders H I, in connection with the drivers L and pins M N, will be rendered apparent from an inspection of Figs. 2 and 3. The pin-chambers in the cylinders

lettered H I, respectively, being in line with the chambers J in the cylinder D, the springs K, operating through the drivers L, maintain a downward pressure on the pins M N, in order that when the key R is inserted through the slot Q the lower ends of the pins N will enter the clefts of the key, and the upper ends of the pins M and lower ends of the drivers L will have a regular line of union at the meeting edges of the cylinder H with the cylinder D, as shown in Fig. 2, thereby permitting of the rotation of the cylinders by the means of the key R, the cylinders H I at this time being connected by the irregular line of meeting edges between the pins M N. Upon the rotation of the cylinders H I, under the condition of the pins illustrated in Fig. 2, the walls of the inner end of the slot Q will engage the sides of the ward *a* and cause the rod W to rotate, thereby bringing the arm *n* of the revolute plate *k* upward into contact with the tumbler *r* and bolt *t* and actuating said bolt either to lock or unlock the door. The pins M N, upon the withdrawal of the key R will assume their normal positions with respect to each other. The key R, being the minor key, will be supplied to the tenants, and while it will unlock the door prepared for it, it will be ineffective on any of the other doors of the building, said other doors having locks in which the pins M N will vary in length.

When it is desired to unlock the door for the purpose of inspecting or cleaning the room, the janitor will use the major key S, which, upon being introduced into the slot Q, will cause the pins M N to have a regular line of union between the cylinders H I, while the upper ends of the pins M will connect the cylinder H with the cylinder D in an immovable manner, as illustrated in Fig. 3, in which condition, upon turning the key S, the cylinder I will rotate and cause the locking or unlocking of the door through the medium of the rod W, ward *a*, and arm *n* on the revolute plate *k*. It will thus be seen that the door may be opened by either the key R or the key S from the outer side of the door, or by the rod W from the inner side of the door, the keys R S being entirely different in outline.

The "combinations" formed by the pins M N will vary to suit the different minor or tenants' keys R throughout the various apartments of the building; but all of these combinations will be arranged with respect to the outline of the major key S, which may be utilized for unlocking all of the apartments of the building. It will only be necessary, therefore, for the proprietor or janitor to carry one key S for access to all of the apartments, while the various tenants will each be supplied with a different key.

What I claim as my invention, and desire to secure by Letters Patent, is—

1. In a lock, the combination of a rotary key-hub and a rotary cylinder surrounding

it, said cylinder having tumbler-recesses, substantially as and for the purposes set forth.

2. In a lock, the combination of a key-hub, a cylinder surrounding it, and tumblers to fasten the two together or to unfasten them, so that they may be rotated together or the key-hub rotated alone, substantially as set forth.

3. In a lock, the combination, with a key-hub and a surrounding cylinder, of tumblers consisting of three parts arranged to be formed in two combinations, so as to permit the cylinder and the key-hub or the key-hub alone to be rotated, substantially as set forth.

15 4. The escutcheon - cylinder containing spring-drivers and inclosing cylinder H I, carrying pins M N, and the inner cylinder be-

ing provided with the key-slot Q, combined with the rod W, having ward a, the revoluble plate k, having arm n, and the tumbler and bolt, substantially as and for the purposes set forth.

5. The bolt W, having the ward a, spring g, and head b, combined with the revoluble plate k on the said rod, and having the arm n, combined with the tumbler r and bolt t, substantially as and for the purposes set forth.

Signed at New York, in the county of New York and State of New York, this 12th day of January, A. D. 1889.

EDWARD J. O'KEEFE.
